RECEIVER DETECTOR CONTROL

David Grimes, Dongan Hills, Staten Island, N. Y.,
assignor to Radio Corporation of America, a
corporation of Delaware

Application June 12, 1931, Serial No. 543,857

13 Claims. (Cl. 250—20)

My present invention relates to radio receivers, and more particularly to a method of, and means for, regulating the second detector of a superheterodyne receiver.

Experience with a superheterodyne receiver of a well-known type has disclosed the fact that there exists a limiting overloading point for the power tube, or tubes, of the receiver, after which point variation of the volume control instrumentality towards its maximum setting results in a decrease in volume, or stated differently in an apparent de-tuning of the receiver. In other words, it has been found, for a type of superheterodyne receiver which includes the usual local oscillator, signal circuit, frequency changer tube, intermediate frequency amplifier tubes and second detector, that as the volume control agency is increased up to a certain point of radio frequency input, the loud speaker output increases and distortion increases at power tube overload, and that as the volume control device which regulates the radio frequency gain is still further increased beyond this point the output of the receiver drops appreciably, and causes confusion in volume control and tuning operations.

This phenomenon may be attributed to the second detector tube. It was found that the control electrode of the said tube became positive on strong signals, thus drawing current.

Now, I have discovered a method of, and devised means for, alleviating the aforementioned difficulty in receivers, and superheterodyne receivers specifically, by utilizing a compensating device in the control electrode circuit of the last intermediate frequency amplifier tube so that shortly after the second detector has overloaded the control electrode of the said intermediate tube assumes a positive charge, thus building up a negative voltage in addition to its predetermined bias, and thereby reducing the intermediate gain with consequent mitigation of second detector overload.

Accordingly, it is one of the main objects of my present invention to provide, in a superheterodyne receiver employing at least one intermediate frequency amplifier tube, a system for substantially reducing second detector overload in the receiver after the power tubes have been overloaded, and when the volume control instrumentality is still further increased.

Another important object of the present invention is to provide in a superheterodyne receiver comprising a signal circuit, a local oscillator, a frequency changer device, an intermediate frequency amplifier including means in the grid-

cathode circuit of one of the intermediate amplifiers for controlling the volume of the set, and one, or more, power tubes, a compensation circuit in the grid-cathode circuit of said intermediate tube to reduce the intermediate amplification when the signals on said intermediate tube become strong enough to overload the second detector.

Still another important object of the present invention is to provide in a radio receiver including a radio frequency amplifier, a detector and an audio frequency amplifier, the detector being designed to overload subsequent to the audio amplifier for optimum operating efficiency, an arrangement for substantially reducing said detector overload immediately after the detector overloads.

And still other objects of the present invention are to improve generally the efficiency of radio receivers, and to particularly provide a detector overload control which is efficient in operation.

The novel features which I believe to be characteristic of my invention are set forth in particularity in the appended claims, the invention itself, however, as to both its organization and method of operation will best be understood by reference to the following description taken in connection with the drawing in which I have indicated diagrammatically one organization whereby my invention may be carried into effect.

In the drawing,

Fig. 1 graphically illustrates the operation of a superheterodyne receiver, as shown in Fig. 4, with, and without, the present invention embodied in said receiver.

Fig. 2 is a graphical representation of the operation of a superheterodyne receiver, as shown in Fig. 4, during a certain range of volume control variation.

Fig. 3 is a graphical representation of the operation of the same receiver, during a succeeding portion of the volume control variation.

Fig. 4 diagrammatically shows a superheterodyne receiver embodying the present invention.

Referring to the accompanying drawing in which like characters of reference indicate the same parts in the different figures, there is shown in Fig. 4 a conventional, and well known, type of superheterodyne receiver sold extensively for radio broadcast reception. This receiver usually comprises a grounded antenna system A, G, the input of a radio frequency amplifier being coupled to the grounded antenna. The said amplifier is conventionally represented, and, as is well known to those skilled in the art, com-

prises one, or more, tuned stages of radio frequency amplification, each stage embodying an electron discharge tube of the triode or screen grid type.

5 The variable condenser 1 conventionally represents the fact that the amplifier is tuned to a desired signal. The output of the tuned radio frequency amplifier is impressed upon a frequency changer device, or a first detector, this 10 device being conventionally represented. The detector usually comprises a triode, or screen grid, tube, it being understood of course that the input circuit of this device may also be tuned to the signal frequency.

15 A local oscillator, conventionally represented, impresses local oscillations of a frequency sufficient to produce beats of a super-audible, or intermediate, frequency with the signal frequency oscillations. The variable condenser 2 is to be 20 understood as functioning to control the frequency of the local oscillations. As is well known in the art, a mechanical uni-control device 3 is employed for continuously varying both condensers 1 and 2 throughout the broadcast range, 25 any well known means being employed for maintaining a constant difference frequency between the signal and local oscillator circuits. This is not part of the present invention, and therefore need not be further described in any further detail.

30 The difference, or intermediate, frequency, is impressed upon the input circuit of the first intermediate frequency amplifier tube 4 through a transformer coupling, as at M, it being noted 35 that the first tube is of the screen grid type. The input circuit of the tube 4 is maintained fixedly tuned, by means of a relatively fixed condenser 5, to the desired super-audible difference frequency. A resistor 7 shunted by a by-pass capacity 6, provides the necessary bias for the grid 40 of the tube 4. The output circuit of the first intermediate amplifier tube is maintained fixedly tuned, by a relatively fixed capacity 5', to the intermediate frequency, and the amplified intermediate frequency energy is impressed, 45 through a transformer coupling 8, upon the input circuit of a second intermediate frequency amplifier tube 9.

50 The second intermediate amplifier tube, also, has its input circuit fixedly tuned, by means of a relatively fixed condenser 10, to the intermediate frequency, bias for the grid of the tube 9 being secured by means of an arrangement 6', 55 7', similar to that shown in connection with the tube 4. The tube 9 is of the screen grid type, and its output circuit is preferably also maintained fixedly tuned, by means of a relatively fixed condenser 10' to the desired intermediate frequency.

60 The second intermediate amplifier tube is followed by a second detector tube, which tube may be of the triode, or screen grid type, the input of the second detector being maintained fixedly tuned, by a relatively fixed condenser 11, 65 to the intermediate frequency. The detected intermediate frequency energy is, then, amplified by means of any well known type of audio amplifier, the latter embodying one, or more, stages of audio frequency amplification, and each 70 stage embodying an electron discharge tube. The last audio tube, or power tube, (which power stage as is well known to those skilled in the art may, if desired, comprise a pair of tubes connected in push-pull) is usually connected to any 75 well known type of utilization means, such as a

loudspeaker of the electromagnetic or electrodynamic type, or even head phones if desired.

It will be observed that the grid biasing resistor 7' in the grid-cathode circuit of the second intermediate amplifier tube 9 is shown variable. It will be understood that the resistor 7' is adjustable in order to enable it to function as to the volume control instrumentality of the receiver. Clearly, this is not essential since the gain control device may be disposed in any other 10 stage, as the radio frequency amplifier.

Obviously, by varying the magnitude of the resistor 7', the amount of negative bias impressed upon the grid of the tube 9 can be regulated, with the result that the gain of the intermediate 15 frequency amplifier is controlled.

In Fig. 1, there is graphically shown a series of curves which represent the operation of the receiver shown in Fig. 4, with, and without, the present invention embodied therein. Curve B 20 illustrates the relation between loudspeaker output and radio frequency input after the magnitude of the resistor 7' is varied between its minimum and maximum values. As the volume control (it will be understood hereinafter that the variable resistor 7' with its associated volume control on the operating panel of the set is included within the meaning of the term "volume control device") is increased so as to produce a radio frequency input variation from 30 point o to a, it is found that the loudspeaker output increases in a substantially linear manner, as shown between points o and a on curve B.

With the volume control fixed at some point below a on Fig. 1, there is obtained the curve B', 35 shown in Fig. 2, as the tuning control 3 is tuned through a station. In other words, assuming that the volume control resistor 7' is adjusted to a point which will yield a radio frequency input lying between points o and a, variation of 40 the tuning knob 3 through any given station setting will produce the relation represented by curve B' between the loudspeaker output and the tuning condenser variation. Of course, at the resonance point s, the volume and quality for any 45 given station will be best, due to the presence of both the carrier and side bands.

Referring again to Fig. 1, as the volume control 7' is now increased between points which will yield radio frequency inputs between points 50 a and b on curve B, it will be found that loudspeaker output and distortion both increase. The distortion is denoted by the departure of the curve from its linear path. The point a on curve B is the point at which the power tubes overload, 55 or stated otherwise is the point at which the grid of a power tube draws current. It has been found in a superheterodyne receiver of the type shown in Fig. 4, that this point X is 3 watts.

Now, as the volume control is still further 60 varied so as to increase the radio frequency input, it is found that the loudspeaker output drops appreciably, and causes confusion in operation. This is represented on curve B in Fig. 1, by the portion of the curve between points b and c. It 65 will be seen that the loudspeaker output between these two points takes a very appreciable drop, and that at the point c it rises very slowly. The significance of the phenomena occurring between points b and c, to the operator of the set, 70 is graphically shown in Fig. 3. It may be stated now that at the point b the second detector overloads.

Fig. 3 shows the same relations as has been 75 shown in connection with Fig. 2. The curve

w represents the relation between tuning condenser variation and loudspeaker output through any station, if line P, Q were followed in Fig. 1, subsequent to point a. That is, line P, Q represents an ideal condition of no overload of second detector and power tube. It is to be noted that the curve w is analogous to the resonance curve B' shown in Fig. 2, the curve w merely being amplified, since that is what would happen ideally if the relationship in Fig. 1 continued along the linear path between points o and a.

However, due to detector and power tube overload produced by varying the volume control between points b and c, a double peak occurs which confuses tuning on loud stations, and often results in the set operator actually de-tuning the receiver to rectify what appears to him to be an apparent de-tuning of the set. This is illustrated by the double peak curve B'' in Fig. 3. In other words, when the set operator varies the volume control between points b and c the decrease in loudspeaker output is often interpreted by the operator as de-tuning.

Believing that the set is tuned to a point s on the curve B'' in Fig. 3, the set operator shifts the tuning instrumentality 3 to point t, with the result that there is lost all side bands carrying the low audio tones. On the other hand, if the set operator does not readjust the tuning device to correct the apparent de-tuning, but reduces the volume control, the loudspeaker output increases upwards along the slope between points c and b in Fig. 1, thus making it appear to the operator that the volume control is working backwards. That is to say, the operation of the volume control will appear still more confusing, since it will apparently increase the output of the receiver when it should be decreasing it.

In spite of the desirability of deferring detector overload for maximum volume and quality until the power tubes have overloaded, the confusion in operation at detector overload still exists, because the operator may have inadvertently adjusted the volume on his receiver to a position that has maximum power tube output.

This trouble is caused by the grid of the detector tube running positive upon strong signals, the grid drawing current in such cases. In superheterodyne receivers where there exists a large inductance in the input circuit of the second detector tube and a small value of capacity, the circuit maintained tuned by the fixed capacity 11, for example, has a relatively high impedance, with the result that the grid-cathode resistance of the tube, as the grid runs positive, acts as a serious load on the tuned circuit causing an appreciable drop in radio frequency voltage on the grid of detector tube. This drop is sufficient to cause the change in loudspeaker output shown by that portion of the curve B, in Fig. 1, which lies between the points b and c.

A method of eliminating this drop in radio frequency voltage on the grid of the second detector tube comprises the insertion of a compensation circuit in the grid circuit of the preceding tube 9. This compensation circuit comprises a fixed capacity 20 having its high potential side connected to the low potential sides of the inductance and capacity in the grid-cathode circuit of the tube 9, the low potential side of the capacity 20 being grounded. A resistor 21 is connected in shunt with the capacity 20, and functions as a leakage path.

As soon as the grid of tube 9 runs positive, the entire grid circuit builds up a negative voltage,

in addition to its predetermined bias, thus reducing the amplification so as to materially reduce the following detector overload. An example of the values of the elements in the compensation circuit, it being understood that these values are merely given by way of illustration, comprises giving the capacity 20 a value of one microfarad, and giving the resistor 21 a value of one-half megohm.

Normal bias is supplied by the resistor 7' in the grid-cathode circuit. No direct current voltage is built up across capacity 20 and resistor 21 until the grid of tube 9 runs positive and draws electrons. As soon as the grid begins to assume a positive charge, the capacity 20 commences to accumulate a charge, adding to the negative voltage on the grid of tube 9, thereby reducing the intermediate amplification to prevent second detector overload.

The operation of the receiver, when embodying the present invention, is graphically shown in Fig. 1 by the curve A'. This last curve clearly illustrates what happens when the compensation circuit 20, 21 is inserted in the grid circuit of the intermediate amplifier tube 9. It is believed obvious from the foregoing explanation, and the graphical representation in Fig. 1, that the utilization of the compensation circuit in the grid circuit of an intermediate amplifier tube effectively eliminates the operating disadvantage graphically represented in Fig. 3. Of course, the invention is not limited to utilization in the second intermediate amplifier tube, but may be used in the first intermediate tube as well.

Furthermore, the present invention is not limited to superheterodyne receivers. Broadly stated, it applies to any radio receiver employing a radio frequency amplifier, a detector and a succeeding audio amplifier. For example, the detector may be of the "power detector" type working into a single power audio amplifier stage, such detector usually having high potentials applied to the grid and anode thereof. In such cases, it is highly desirable to have the detector overload subsequent to the power tube, the arrangement hereinbefore described, then, co-operating with the radio frequency amplifier, usually of a high gain, to diminish detector overload in the manner described.

Of course, the second detector of the superheterodyne receiver in Fig. 4 may be of the power type, whereby only a single power audio tube need be used in such a case.

While I have indicated and described one arrangement for carrying my invention into effect, it will be apparent to one skilled in the art that my invention is by no means limited to the particular organization shown and described, but that many modifications may be made without departing from the scope of my invention as set forth in the appended claims.

What I claim is:

1. In combination with a superheterodyne receiver including an intermediate frequency amplifier consisting of an electron discharge tube provided with a grid circuit tuned to a desired intermediate frequency, means in the cathode circuit of said tube for biasing the grid of said intermediate amplifier tube, and additional means in the grid circuit of said tube for increasing the bias on the grid when surging positive with strong signals.

2. In combination with a superheterodyne receiver including an intermediate frequency amplifier consisting of an electron discharge tube 75

- provided with a grid circuit tuned to a desired intermediate frequency, means in the cathode circuit for biasing the grid of said intermediate amplifier tube, and a compensation circuit in the grid circuit of said tube for increasing the negative bias on the grid when surging positive with strong signals.
3. In combination with a superheterodyne receiver including an intermediate frequency amplifier consisting of an electron discharge tube provided with a grid circuit tuned to a desired intermediate frequency, means in the cathode circuit of the tube for biasing the grid of said intermediate amplifier tube, and additional means including a capacity shunted by a resistor in the grid circuit of said tube for increasing the bias on the grid when surging positive with strong signals.
4. In combination with a superheterodyne receiver including an intermediate frequency amplifier consisting of an electron discharge tube provided with a grid circuit tuned to a desired intermediate frequency, means for biasing the grid of said intermediate amplifier tube, and additional means in the grid circuit of said tube for increasing the bias on the grid when surging positive with strong signals, said first named biasing means comprising a variable resistor in the grid-cathode circuit of said tube.
5. In combination with a superheterodyne receiver including an intermediate frequency amplifier consisting of an electron discharge tube provided with a grid circuit tuned to a desired intermediate frequency, means for biasing the grid of said intermediate amplifier tube, and a compensation circuit in the grid circuit of said tube for increasing the bias on the grid when surging positive with strong signals, said first named biasing means comprising a variable resistor in the grid-cathode circuit of said tube.
6. In combination with a superheterodyne receiver including an intermediate frequency amplifier consisting of an electron discharge tube provided with a grid circuit tuned to a desired intermediate frequency, means for biasing the grid of said intermediate amplifier tube, and additional means including a capacity shunted by a resistor in the grid circuit of said tube for increasing the bias on the grid when surging positive with strong signals, said first named biasing means comprising a variable resistor in the grid-cathode circuit of said tube.
7. In a receiver including a detector and preceding amplifier tube, an arrangement for alleviating detector overload comprising an accumulator circuit in the grid circuit of the preceding amplifier tube designed to acquire a negative charge as signals sufficiently strong to overload said detector swing the grid potential of said preceding tube positive.
8. In combination, in a radio receiver, a radio frequency amplifier, a detector, an audio amplifier, said detector being designed to overload subsequent to said audio amplifier, and additional means, associated with the radio frequency amplifier operative to decrease the amplification thereof in response to signals of an intensity which would overload the detector.
9. In a superheterodyne receiver of the type having an audio frequency amplifier adapted to overload prior to the second detector thereof and an intermediate frequency amplifier feeding into the second detector, the method of preventing decrease in receiver volume caused by overloading of the said detector which includes so adjusting the circuit constants of said intermediate frequency amplifier that the gain of the intermediate frequency amplifier is decreased solely in response to signals of detector overloading.
10. In a superheterodyne receiver, a second detector stage having circuit constants such that the receiver volume decreases when the detector is overloaded, an audio frequency amplifier arranged to overload prior to overloading of said detector, an intermediate frequency amplifier preceding said detector including adjustable bias means for varying the amplification thereof, and additional means electrically associated with the intermediate frequency amplifier for varying the amplification thereof independently of said adjustable bias means in response to signals of an intensity which would overload the detector.
11. In a superheterodyne receiver, a second detector stage having circuit constants such that the receiver volume decreases when the detector is overloaded, an audio frequency amplifier arranged to overload prior to overloading of said detector, an intermediate frequency amplifier preceding said detector including adjustable bias means for varying the amplification thereof, and additional means electrically associated with the intermediate frequency amplifier for varying the amplification thereof in a direction opposite to that of said adjustable bias means in response to signals of an intensity which would overload the detector.
12. In a radio receiver of the type having an audio frequency amplifier adapted to overload prior to the detector thereof, the method of preventing undesirable decrease in receiver output volume caused by overloading of the detector which includes so adjusting the efficiency of the transmission of signals through the receiver prior to detection that said prior transmission will be automatically decreased solely in response to signals of an intensity which would overload the detector.
13. A method of preventing apparent de-tuning in a radio receiver, which is caused by reproduction volume decrease when the detector of the receiver overloads subsequent to the audio frequency amplifier, consisting in amplifying the signals prior to detection, and causing a decrease in the said signal amplification solely in response to signals of detector overloading intensity.

DAVID GRIMES.
